UNITED STATES PATENT OFFICE.

BERNARD J. DEVER, OF OAKLAND, CALIFORNIA.

SELF-RAISING SEAT.

Application filed December 13, 1926. Serial No. 154,456.

This invention relates particularly to chairs adapted for use in theatres, auditoriums and the like.

An object of the invention is to provide a chair having a seat thereon, which will normally stand in an upright position, and which may be manually placed into initial and secondary sitting positions, to allow a person to sit thereon, and which will automatically return itself to an upright position after the weight of the person seated thereon has been removed.

A further object of the invention is to provide a chair with a seat thereon capable of being positioned in either an upright or a substantially horizontal sitting position, and so constructed as to automatically return itself from the sitting to the upright position upon the removal of a pressure applied to said seat in the sitting position.

A still further object of the invention is to provide a chair with an automatic seat raising mechanism thereon so arranged that said seat may be placed in an initial sitting position to receive the weight of a person thereon, and which after the seat has received the weight of a person thereon, is released from a secondary sitting position and restored to a substantially vertical position.

Other objects of the invention are to provide a chair with a seat raising mechanism thereon which will be superior in point of simplicity and inexpensiveness of construction, positiveness of operation, facility and convenience in use and general efficiency.

In this specification and the annexed drawings, the invention is illustrated in the form considered to be the best, but it is to be understood that the invention is not limited to such form, because it may be embodied in other forms, and it is also to be understood that in and by the claims following the description, it is desired to cover the invention in whatsoever form it may be embodied.

In the accompanying three sheets of drawings,

Fig. 1 represents a vertical section taken through a chair having an automatic mechanism for raising the seat thereon, constructed in accordance with my invention.

Fig. 2 is an enlarged section taken on the line 2—2 of Fig. 5, showing a seat raising mechanism constructed in accordance with my invention in the inoperative position.

Fig. 3 is a vertical section through the

mechanism placed on the opposite side of the seat to which the mechanism shown in Fig. 2 is placed, to assist in raising the seat into a vertical position.

Fig. 4 is a section similar to Fig. 2 showing the mechanism in the sitting or operative position.

Fig. 5 is a section taken through Fig. 2 on the line 5—5.

Fig. 6 is a section of the seat pivot taken through Fig. 5 on the line 6—6.

Fig. 7 is a fragmentary plan section taken on the line 7—7 of Fig. 2.

Fig. 8 is a vertical section taken through Fig. 2 on the line 8—8.

In detail, the construction illustrated in the drawings comprises a chair formed of the opposite side stands 1, connected by the back 2. The chair back and sides are conventional, and no portion of my invention concerns itself with any specific type of chair back or chair side. A seat 3 is arranged between the side supports 1 and is pivotally mounted on the respective trunnions 4 and 4' secured to each of the opposite sides 1. A bracket 5 is provided on each of the opposite bottom edges of the seat 3, each bracket having an arm 6 that projects therefrom into spring housings 7 and 7' loosely mounted on the trunnions 4 and 4' on each chair side. The bracket 5 and the spring housing are provided with co-engaging projections 6 and 8 thereon, to be moved by the chair seat into the initial and secondary sitting positions.

The seat mountings, adjacent the trunnions on each of the opposite sides of the seat, are different in construction. On one side of the seat I mount a spring housing 7, to pivot about the trunnion 4 between the seat edge and one side support 1, as shown in Fig. 3. A clock or spiral spring 9 is arranged around the trunnion 4 within the housing 7. One end of the spring 9 engages the trunnion 4, while the opposite end of the spring engages a latch 10 on the housing 7. The latch 10 is adjustable between the spring end and housing, so that the tension of the spring may be regulated. The arm 6 on the bracket 5 on the seat engages the end 8 of the spring housing 7 so that when the seat is moved into the initial sitting position, from the vertical position shown in Fig. 3, in the direction of the arrow "A", the spring housing 7 will be rotated about the trunnion 4 to wind the

spring 9. When the seat is placed in the initial sitting position, at or about an angle of 80° from the vertical position, the weight of the seat and the leverage exerted thereby on the seat fulcrum will be sufficient to retain said seat in the initial sitting position and to overcome the unwinding action of the spring which might otherwise tend to restore said seat to the vertical position.

10 The spring 9 is used primarily to maintain the seat in the vertical, inoperative position or to assist the spring 13 on the opposite side of the seat to raise the seat from the secondary sitting position back into the vertical, inoperative position.

On the opposite side of the seat 3 adjacent the trunnion 4' I have arranged my seat raising apparatus. The arm 6 that extends from the seat bracket 5 engages the 20 end 12 of the spring housing 7'. My invention relates particularly to means adjacent the trunnion 4' and between the seat side 1 and seat bracket 5 to automatically raise or return the seat to an upright position, after a weight that has been applied to said seat, (when in a substantially horizontal position, causing said seat to be depressed from an initial seating position into a secondary sitting position) has been removed to restore the seat from the secondary sitting position to the vertical inoperative position. To accomplish this raising of the seat I provide a clock or spiral spring 13 within the housing 7'. One end of the 30 spring 13 is secured to the trunnion 4' while the opposite end of the spring is secured to a latch 14 that extends from one side of a disc or plate 15 that is journaled on the trunnion 4' adjacent the spring 13. The 40 housing 7' covers one side of the spring 13 while the disc 15 covers the opposite side of the said spring.

An arm 16 is pivoted at 17' to the inside face of one of the seat supports 1. A link 17 is pivoted at 18 to the free end of the arm 16 while the opposite end of the link 17 is pivoted at 19 to a face of the disk 15 that is mounted on the trunnion 4'. In Fig. 2 I have shown the seat 3 and spring housing 7' in a substantially vertical position and in readiness to be moved into the horizontal sitting position. When the seat is swung downward into the sitting position, the arm 6 on the seat engages the end 50 12 of the spring housing 7' and moves the spring housing 7' in the direction of the arrow "B" until such time as the said spring housing 7' reaches the dotted position shown in Fig. 2 which is the initial sitting position. The spring 9, shown in Fig. 3, is not of sufficient strength to return the seat to the upright position, and hence the weight of the seat will cause it to remain 60 in the dotted horizontal position shown in Fig. 2, in contact with a projection 20 on

the arm 16. The projection 20 is padded at 21 so that no noise will result from contact with the end 12 of the spring housing 7'. The unwound spring 13, through the disc 15, links 17 and arm 16, will resist any articulating movement of the assembly due to the engagement of the spring housing 7' with the projection 20 on the arm 16.

In Fig. 1, I have shown the initial and secondary sitting positions of the seat by 75 dotted lines, and in Fig. 2 I have shown an enlarged view of the parts of the seat raising mechanism in the initial sitting position. When the seat is in the initial position, it is ready to be sat upon. When the 80 weight of a person is applied to the seat in the initial position, the seat is depressed into the secondary sitting position, which causes the spring housing 7' to engage the projection 20 on the arm 6 to move the articulated parts of the seat raising mechanism into the position shown in Fig. 4, thereby winding the spring 13. In Fig. 4 the seat is in the secondary sitting position, with the spring 13 wound, and from which position the seat 90 may be restored to the upright position by the unwinding of the spring after removing the weight of the person from the seat.

My seat raising mechanism does the greater part of its operating when it is moved 95 from the initial into the secondary sitting positions. The initial position of the spring housing 7' shown by dotted lines in Fig. 2, shows it to be engaged with the padded bracket 20 on the arm 16. By subsequently depressing the seat into the secondary sitting position, the arm 16 is swung by the seat movement into the position shown in Fig. 4, causing the link 17 to rotate the disk 15 around the trunnion 4', and to wind the 100 spring 13. In unison with the rotary movement of the disk 15 and the spring 13, a dog 105 22 that is pivoted at 23 to the inside of the spring housing 7' is engaged with a projection 24 on the disk 15. When the spring housing 7' is moved into the initial sitting 110 position, shown by dotted lines, in Fig. 2, the dog 22 is moved therewith and allowed to drop (into the dotted position shown in Fig. 2) in contact with the periphery of the 115 disk 15. The connected levers 16 and 17 are actuated and the spring is wound by the seat 3 moving from the initial into the secondary sitting position. Likewise the disk 15 is rotated relative to the dog 22 to move 120 the projection 24 on said disk from beneath the under edge of the dog 22 to allow the end of said dog to drop behind the projection 24.

The seat raising mechanism will stay in 125 the secondary sitting position until such time as the weight of the person on the seat is removed therefrom. When the person arises from the seat, the spring 13 will unwind, to rotate the projection 24 on the disk 130

15 into contact with the end of the dog 22 to consequently rotate the dog and spring housing 7', in the direction of the arrow "C", until such time as the seat arrives in the vertical inoperative position. The spring 9, shown in Fig. 3, assists the spring 13, shown in Figs. 2 and 5, in elevating the seat from the secondary sitting position into the elevated inoperative position.

10 I have provided a guide pin 25 on the spring housing 7' to engage the dog 22 and to prevent said dog from falling into a position where it may be inoperative. I have provided a pad or stop 26 to engage the 15 end of the bracket 5 on the seat to stop said seat in a proper vertical position.

The leverage obtained by moving the seat from the vertical into the horizontal position is sufficient to wind the springs on the 20 opposite sides of the seat, and the tension of the wound springs is sufficient to cause the seat to be raised, at such time when the moving force is removed from said seat. The unwinding of the springs about the trunnions would not be sufficient to raise the seat, hence it is necessary to provide the dog 22 actuated by the unwinding spring, to apply the spring energy to the extended end of the spring housing, which produces sufficient leverage to raise the seat from the 25 horizontal to the vertical position.

Having thus described this invention, what I claim and desire to secure by Letters Patent is:

35 1. In combination a chair frame having a seat pivotally mounted thereon; a disc rotatably mounted on the seat pivot; a spiral spring around the seat pivot having one end thereof secured to said pivot and the other 40 end secured to the disc; a jointed arm having one end pivotally secured to the chair frame and the other end pivotally secured to the disc; means on the chair seat to engage the jointed arm to move the arm and disc to wind the spring as the seat is swung from a vertical to a horizontal position; and means interposed between the wound spring and seat to swing the seat from a horizontal 45 to a vertical position.

50 2. In combination a chair frame having a seat pivotally mounted thereon; a disc rotatably mounted on the seat pivot; a spiral spring around the seat pivot having one end thereof secured to said pivot and the other 55 end secured to the disc; a jointed arm having one end pivotally secured to the chair frame and the other end pivotally secured to the disc; means on the chair seat to engage the jointed arm to move the arm and disc to wind the spring as the seat is swung

from a vertical to a horizontal position; and a latch on the seat to engage the spring disc when the seat is in the horizontal position to transmit the unwinding action of the spring to the seat to raise the seat from a 65 horizontal to a vertical position.

3. In combination a chair frame having a seat trunnion arranged at corresponding points on each of the opposite sides thereon; a seat having its opposite side edges journaled on the respective trunnions; a housing rotatably mounted on one of the seat trunnions between the seat edge and chair frame; a disc rotatably mounted on the said trunnion adjacent the housing; a spiral 70 spring mounted around the said trunnion between the disc and housing, said spring having one end thereof secured to the trunnion and the opposite end secured to the disc; a jointed arm having one end pivotally secured to the chair frame and the opposite end pivotally secured to the disc; means on the seat to move the housing into engagement with the jointed arm to actuate the arm and disc to wind the spring as the seat 75 is swung from a vertical to a horizontal position; and means interposed between the wound spring and housing to swing the seat from a horizontal to a vertical position.

4. In combination a chair frame having a seat trunnion arranged at corresponding points on each of the opposite sides thereof; a seat having its opposite side edges journaled on the respective trunnions; a housing rotatably mounted on one of the seat 80 trunnions between the seat edge and chair frame; a disc rotatably mounted on the said trunnion adjacent the housing; a spiral spring mounted around the said trunnion between the disc and housing, said spring having one end thereof secured to the disc; a jointed arm having one end pivotally secured to the chair frame and the opposite end pivotally secured to the disc; means on the seat to move the housing into engagement with the jointed arm to actuate the arm and disc to wind the spring as the seat 85 is swung from a vertical to a horizontal position; and means interposed between the wound spring and housing to swing the seat from a horizontal to a vertical position.

In testimony whereof, I have hereunto set my hand at San Francisco, California, this 26th day of November, 1926.

BERNARD J. DEVER.
